[57] ABSTRACT

A dual-mode encoding and decoding procedure enables image data to be compressed optionally in one-dimensional (1D) mode or two-dimensional (2D) mode. In 1D mode, color transitions in the image are encoded as run length features only. In 2D mode, the transitions are encoded as vertical correlation features wherever possible, and where this is not possible, the transitions are encoded as run length features. The compression

achieved by run length encoding in 2D mode may be enhanced in those instances where the "history line" which precedes the current scan line contains a transition located between points that are vertically aligned with the beginning and end points of the run currently being encoded. Run length counting is suspended for those pels in the current run that could have been referenced to the history transition if the run had ended with any of these pels, thereby enabling the run to be encoded as though it contained fewer pels than its actual length. Compression may be enhanced still further by dynamically interchanging the variable-length bit patterns respectively representing certain vertical correlation and run length prefix codes depending upon whether the preceding transition was encoded as a vertical correlation feature or a run length feature.

STATE DIAGRAM FOR ENCODER STEP 1 (TWO DIMENSIONAL MODE,
WAIT CONDITION)

The diagram illustrates the sequence of events: WAIT, LINE SCAN, and READY. The sequence is repeated three times, each time starting with a WAIT. The events are represented by arrows pointing from one state to the next. The states are labeled as follows:

- WAIT
- LINE SCAN
- READY
- WAIT
- LINE SCAN
- READY
- WAIT
- LINE SCAN
- READY

Below the diagram, three tables show the simulated operation of the encoder for three lines (Line 1, Line 2, Line 3) across four cycles (Cycle 0, Cycle 1, Cycle 2, Cycle 3). The tables include columns for CYCLE NO., LINE, and OUTPUT (DRL, EZ, RL, W1, W2, W3, W4).

CYCLE NO.	12	13	14	15	16	17	18	19	20	21	22	23	24	25	26	27	28	29	30	31	32	33
LINE 1	1	0	0	0	1	1	0	0	0	0	1	1	0	0	0	0	1	1	1	0		
OUTPUT	DRL	DRL	DRL	DRL	W3	B1	B2															

CYCLE NO.	40	41	42	43	44	45	46	47	48	49	50	51	52	53	54	55	56	57	58	59	60	61
LINE 2	0	0	0	0	1	1	0	0	0	0	0	1	1	0	1	1	0	1	1	0	0	0
OUTPUT					EZ			EP			EP			EP	EM	RL						

CYCLE NO.	68	69	70	71	72	73	74	75	76	77	78	79	80	81	82	83	84	85	86	87	88	89
LINE 3	1	1	0	0	0	0	0	0	1	0	0	0	0	0	1	1	1	0	0	0	0	
OUTPUT	RL	RL	RL	RL	W3	B2	B1
